TOY BANK

Walter F. Hess, Royal Oak, Mich.

Application July 22, 1955, Serial No. 37,093

Term of patent 14 years

(Cl. D34—11)

I claim:

The ornamental design for a toy bank, substantially as shown.
